Inventor:

Eli James M.D.

UNITED STATES PATENT OFFICE.

ELI JAMES, OF HUDSON, ASSIGNOR OF ONE-HALF TO AUGUSTA L. MILLER,
OF LIVINGSTON, NEW YORK.

TRUSS.

SPECIFICATION forming part of Letters Patent No. 395,278, dated December 25, 1888.

Application filed September 22, 1886. Serial No. 214,282. (No model.)

To all whom it may concern:

Be it known that I, ELI JAMES, a citizen of the United States, residing at Hudson, in the county of Columbia and State of New York, 5 have invented certain new and useful Improvements in Trusses; and I do declare the following to be a full, clear, and exact description of my invention, which will enable others skilled in the art to which it appertains to 10 make and use the same, reference being had to the accompanying drawings, and to the letters and figures of reference marked thereon, which form a part of this specification.

The object of this invention is to provide a 15 method of supporting the protruding parts in a hernia by means of a truss of peculiar construction, consisting of an encircling belt provided with a pad or presser having an elastic cup-shaped inner surface with rounded edges, 20 which is removably attached to the belt, and having, further, a means of increasing and diminishing the pressure through the agency of thumb-screws moving an interior ball, as will hereinafter more fully appear in the specification, 25 be illustrated in the drawings, and pointed out in the claim.

In the drawings, Figure 1 is a plan view of my device; and Fig. 2 is a cross-section of the same, showing the means of attachment to 30 the belt and the method of applying the pressure to the parts.

The pad B is concave or cup-shaped in form 35 interiorly, has a rounded edge, and is made of elastic material, and contains the ball A, which, through the agency of the screw H, is forced down into the opening of the pad or cup. It is made of rubber or any other suitable material.

C is the body-belt, having at one extremity 40 the perforated end or part C' and at the opposite end the usual buckle or attachment to secure the belt around the body, and it also has the guide c, through which the holder D passes, which latter is secured to the belt by 45 the screw F and retained by the clamp f.

The holder D is a metallic bar or plate having threaded perforations to receive the thumb-screws E, which enter screw-threaded openings in a plate, G, abutting against the

ball A inside the pad, and by moving the said 50 screws E the ball may be released. Said screws hold the plate G in position. A screw, H, passing through an opening in the center of the holder D, enables the ball A to be advanced or retracted. This screw H has a seat, 55 G', secured in the ball A, and as the screw H is turned the ball is pressed against the rupture or removed therefrom.

The operation is as follows: The belt having been passed around the body and buckled 60 or otherwise attached, it is obvious that the pad may be placed over or applied to the rupture and pressed down over the same, where its elasticity retains it, when, by moving the thumb-screw H, the requisite amount of pressure 65 will be obtained. As the rim of the cup is elastic and yielding, it will be seen that a vacuum is formed when it is applied to the parts, and through the medium of the screw H the ball may be forced down at any degree 70 of pressure desired, or entirely raised from the rupture, which is not possible where a spring is used to impart a constant or increasing pressure. By means of the screw F the cup may be removed from the belt for 75 cleaning.

Having thus described my invention, what I claim therein as new, and desire to secure by Letters Patent, is—

The combination, in a truss, of the elastic 80 cup-shaped pad adapted, by means of its elasticity, to be pressed down upon the rupture for the purpose of expelling the air within, and to resume its normal shape when the pressure is removed, thus forming a vacuum 85 within the cup, the convex presser or ball adjustably secured to its bottom, and the presser-screw H, securing the presser within the pad, and whereby it may be forced outward against the rupture or inward away from it, substantially 90 as and for the purpose described.

In testimony whereof I affix my signature in presence of two witnesses.

ELI JAMES.
